UNITED STATES PATENT OFFICE.

JOSEPH H. POPE, OF HAMILTON, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

JACK.

Specification of Letters Patent. Patented Aug. 26, 1919.

1,313,909.

Application filed February 2, 1916. Serial No. 75,800.

To all whom it may concern:

Be it known that I, JOSEPH H. POPE, a citizen of the United States, residing at Hamilton, in the county of Essex and State 5 of Massachusetts, have invented certain improvements in Jacks, of which the following description, in connection with the accompanying drawings, is a specification, like reference characters on the drawings indicating like parts in the several figures.

This invention relates to jacks for supporting boots or shoes in shoe machinery such, for example, as heel nailing machines.

In positioning lasted shoes properly to be 10 operated upon the adjustment of the shoe 15 in respect to its angular position requires frequent changes in the angle of each last supporting part of the jack.

The object of the present invention is to 20 provide an improved jack arranged to facilitate the making of the desired adjustments by the operator and to maintain securely an adjustment, once made, even though the parts of the jack may be subjected to heavy pressure during the 25 operation upon the work. When a jack is constructed in accordance with my invention, these advantages are attained without the necessity of making the jack parts heavy or 30 cumbersome, and the operator is, by reason of the ease with which the jack is manipulated, able to maintain a higher rate production by the machine, with less tax on his strength and attention than when jacks of 35 the types heretofore known are used. In the illustrated embodiment of the invention the last bed piece, by which the last is directly supported, is mounted to swing about an axis outside the last and a rigid arm extending from the bed piece is arranged to be 40 locked at a point remote from the said axis, thus securing the benefit of a powerful leverage to maintain the bed piece securely even against heavy pressure tending to dis- 45 place it.

The locking means referred to may conveniently be used for purposes of adjustment by gearing, or similarly connecting it to an adjusting member arranged to be locked to, 50 or unlocked from, the jack post and, preferably, as in the illustrated embodiment of the invention, the adjusting member may be so constructed and arranged that either a limited movement with respect to the jack 55 post may be permitted, or the adjusting

member may be locked to the jack post in any one of several adjusted positions; thus meeting the frequently occurring condition that certain ones of a lot of supposedly uniform lasts have become somewhat worn or 60 broken down in use.

These and other features of the invention will be best understood and appreciated from the following description of a preferred embodiment thereof selected for purposes of illustration and shown in the accompanying drawings, in which—

Figure 1 is a view in side elevation of the jack showing also the die plate of a heel attaching machine with a heel in position to be 70 attached;

Fig. 2 is a view in side elevation of portions of the jack, showing the post in section;

Figs. 3 and 4 are detail views of the locking mechanism, and

Fig. 5 is a view, partly in section, of the locking mechanism as assembled in the jack.

The base 13 of the jack has a vertical 80 socket to receive the adjustable jack post 16, the latter being threaded at its lower end and supported on the base by a large hand nut 14. The upper end of the post is provided with horizontal bearings for the trunnions 22 of the last bed piece. The bed piece is therefore supported so that it can be turned or rocked in the longitudinal plane of a shoe 85 supported thereon. When the jack is used in a heel attaching machine this adjusting movement is required to bring the sole of 90 the shoe into parallel relation with the face of the heel which is to be attached to it. As shown in Fig. 1, the heel is held in position by holding arms 10 beneath the die plate 8 by having nail receiving passages for the at- 95 taching nails.

The last bed piece is made in two parts of 100 which the upper section 24 carries the last pin and is mounted to slide horizontally in transverse undercut ways formed in the lower section 23. From the lower section of the last bed piece an arm 18 extends downwardly and is provided at its lower end with an inwardly extending end 20 which passes through a slot or opening in the last post 16. 105 On its upper surface the end 20 of the arm is provided with rack teeth which are arranged to mesh with a pinion 32 fast upon a shaft 26 journaled in bearings in the post 16. 110

At one end the shaft 26 extends into a boss on the post 16 and is provided with a washer 28 between which and the body of the post is disposed a compression spring 30 acting normally to hold the shaft 26 in its right hand position (Fig. 5) in which the pinion 32 is in mesh with the toothed end 20 of the arm 18 of the bed piece. At its other end the shaft 26 is provided with a hand wheel 36 and it will be apparent that by turning the wheel 36 the arm 18 will be oscillated and the angular position of the bed piece correspondingly changed.

Adjacent to the hand wheel 36 the post 16 is bored out and supplied with a cylindrical filling plug 34 which is rigidly held in place by a set screw and a cylindrical key 44, and is provided with a recess 35 to receive the pinion 32 when the latter is moved out of mesh with the rack 20, as will be described hereinafter. A pin 42 projects from the face of the plug 34 and is adapted to enter one of a series of sockets 40 or a long curved slot 38 formed in the inner face of the hub 25 of the hand wheel 36. It will be seen that when the pin 42 enters one of the sockets 40 the hand wheel is locked rigidly against rotation and consequently the angle of the last bed piece is rigidly maintained. When 30 it is desired to adjust the position of the bed piece the hand wheel 36 is pulled outwardly compressing the spring 30 and carrying the inner surface of its hub out of engagement with the end of the pin 42. 35 whereupon the wheel 36 may be turned to bring another socket opposite the pin 42. In case it is desired to arrange the last bed piece for free angular movement the hand wheel 36 is pulled outwardly and turned 40 sufficiently to enter the pin 42 in the curved slot 38 whereupon a limited rotary movement of the hand wheel is permitted.

When the hand wheel 36 is pulled outwardly to disengage the pin 42 the pinion 45 32 is moved into the recess 35 out of mesh with the toothed end 20 of the arm 18, so that in turning the hand wheel to locate either the sockets 40 or the curved slot 38 in operative relation with the pin 42 no 50 movement is imparted to the arm 18 and the last bed piece. It will thus be seen that the last bed piece may be locked in any desired angular position or may be limited to a predetermined angular movement from 55 any initial position.

While the jack of my invention has been described in connection with a heel attaching machine it may be used to good advantage in any machine wherein it is desired 60 to position accurately a shoe with respect to its longitudinal inclination.

Having thus described my invention, I claim as new and desire to secure by Letters 65 Patent of the United States:

1. A jack comprising a post, a last bed

piece mounted to swing thereon about an axis outside the last, an arm extending rigidly from the bed piece, and locking means constructed and arranged to act upon the arm at a point remote from the axis of the 70 bed piece.

2. A jack comprising a post, a last bed piece mounted upon the top of the post to swing about an axis below the last and having an arm extending downwardly and 75 transversely into an opening in the post, and locking means constructed and arranged to act upon the arm within said opening.

3. A jack comprising a post having a last bed piece pivoted upon an axis outside the 80 last, an arm extending rigidly from the bed piece, and adjusting means constructed and arranged to act upon the arm at a point remote from the axis of the bed piece.

4. A jack comprising a post having a 85 movable last bed piece, an arm rigidly connected to the bed piece, and a gear meshing with the arm at a point remote from the axis of the bed piece constructed and arranged to be locked to the post or to be 90 freely rotatable within predetermined limits.

5. A jack comprising a post having a last bed piece pivoted upon its upper end to swing about an axis below the last, an arm 95 extending downwardly from the bed piece and then inwardly through the post, a gear journaled within the post in mesh with the arm, and a hand wheel outside the post for turning the gear.

6. A jack comprising a post having a 100 movable last bed piece thereon, a hand wheel mounted on the post and constructed and arranged to be locked thereto or to have a turning movement within predetermined limits, and connections for moving the bed piece in response to movement of the hand wheel.

7. A jack comprising a post having a 110 movable last bed piece at its upper end, a hand wheel mounted on the post below its end, means for locking the hand wheel to the post, and connections between the bed piece and hand wheel for adjusting the bed piece.

8. A jack comprising a post having a pivoted last bed piece, a rigid arm extending from the bed piece, and an adjusting wheel arranged to turn on an axis parallel to that of the bed piece and being in operative engagement with the arm.

9. A jack comprising a post having an angularly movable last bed piece, and a hand wheel yieldingly held in position on the post and connected to the bed piece, 125 said wheel and post having a pin and slot connection for limiting the movement of the bed piece relatively to the post.

10. A jack comprising a post having a pivoted last bed piece thereon, an angular arm 130

- extending downwardly from the last bed piece and inwardly through the post and having teeth within the post, a spring 5 carrying a gear meshing with the teeth of the arm, a hand wheel mounted on the shaft and having a long curved slot and a series of sockets, and a pin on the post arranged to enter either the slot or one of the sockets.
- 10 11. A jack comprising a post, a movable last bed piece supported by the post, a toothed arm extending from the bed piece, and a locking device for the arm including a pinion normally meshing with the arm, said device being movable to disengage the 15 arm and pinion and to permit said locking device to be moved into different locking positions.

In testimony whereof I have signed my name to this specification.

JOSEPH H. POPE.

Copies of this patent may be obtained for five cents each, by addressing the "Commissioner of Patents, Washington, D. C."

It is hereby certified that in Letters Patent No. 1,313,909, granted August 26, 1919, upon the application of Joseph H. Pope, of Hamilton, Massachusetts, for an improvement in "Jacks," errors appear in the printed specification requiring correction as follows: Page 1, line 15, second occurrence, for the article "the" read *each*; same page, line 17, for the word "each" read *the*, and line 18, for the word "part" read *parts*; and that the said Letters Patent should be read with these corrections therein that the same may conform to the record of the case in the Patent Office.

Signed and sealed this 30th day of December, A. D., 1919.

[SEAL.]

M. H. COULSTON,

Acting Commissioner of Patents.

Cl. 12—126.
